US0D1077052S

(12) **United States Design Patent** (10) **Patent No.:** **US D1,077,052 S**
(45) **Date of Patent:** **** May 27, 2025**

(54) **INTERLOCKING EDGE GAME BOARD**

(71) Applicant: **Anthony Rose**, Rogers, AR (US)

(72) Inventor: **Anthony Rose**, Rogers, AR (US)

(**) Term: **15 Years**

(21) Appl. No.: **29/893,015**

(22) Filed: **May 24, 2023**

(51) **LOC (15) Cl.** **21-01**

(52) **U.S. Cl.**
USPC **D21/334**

(57) **CLAIM**

The ornamental design for an interlocking edge game board as shown as shown and described.

DESCRIPTION

FIG. 1 is a perspective view of an interlocking edge game board showing my new design;

FIG. 2 is a top view thereof;

FIG. 3 is a left side view thereof;

FIG. 4 is a front view thereof; and,

FIG. 5 is a right side view thereof;

FIG. 6 is a bottom view thereof; and,

FIG. 7 is a back view thereof.

1 Claim, 7 Drawing Sheets
